(57) **CLAIM**

The ornamental design for a breathing apparatus display screen with graphical user interface, as shown and described.

DESCRIPTION

FIG. 1 is a front view of a breathing apparatus display screen with graphical user interface; and,

FIG. 2 is a front view of a second embodiment thereof. The outermost broken lines illustrate a display screen and form no part of the claimed design. The remaining broken lines illustrate portions of the graphical user interface that form no part of the claimed design.
